UNITED STATES PATENT OFFICE.

OSCAR D. ANDERSON, OF CONWAY, SOUTH CAROLINA.

DUMPING-WAGON.

1,272,596.

Specification of Letters Patent. Patented July 16, 1918.

Application filed March 6, 1918. Serial No. 220,730.

To all whom it may concern:

Be it known that I, OSCAR D. ANDERSON, a citizen of the United States of America, and a resident of Conway, county of Horry 5 and State of South Carolina, have invented certain new and useful Improvements in Dumping-Wagons, of which the following is a full and clear specification.

This invention has for its object to provide a dumping body and its supporting frame which can be removably mounted upon the running gear of a wagon after its non-dumping body has been removed.

A further object is to provide a supporting frame for a dumping body which is constructed with a means for detachably engaging the usual bolster standards or stakes, to secure said supporting frame in position on the running gear.

These and other objects hereinafter set forth are attained by the means illustrated in the accompanying drawing, in which—

Figure 1 is a view partly in side elevation and partly in section showing the improved dumping body and its support mounted on the running gear of a wagon;

Fig. 2 is a plan view of a portion of the same, showing the outline of the body in dotted lines;

Fig. 3 is a vertical cross-section on the line 3—3 of Fig. 1; and

Figs. 4 and 5 are detail views of the roller bearings used on the removable supporting frame.

Similar reference numerals in all of the figures of the drawing designate like parts.

This improvement is especially adapted for use in connection with the type of wagon constructed with a body or box which is 40 bodily removable to leave the running gear in condition for use as a lumber wagon for hauling poles, posts or cut lumber. This type of wagon is used extensively on farms, and a farmer possessing one of the hereinabove described bodies and its roller bed, in addition to the regular body, can transform his non-dumping wagon into a dumping wagon without the necessity of using tools or removing bolts.

The running gear of the usual farm wagon embodies a front axle 10, a rear axle 11, a front bolster 12, a rear bolster 13, a reach-bar 14 connecting the two bolsters, so that the front and rear wheels 55 are held in spaced relation, and each bolster is provided at its ends with standards or

stakes 15, which lie on each side of the wagon-body to prevent its transverse displacement, and, when the body is removed, to serve as lumber stakes for retaining logs 60 and lumber on the bolsters.

The improved dump-body attachment comprises a rectangular frame having side-bars 16 permanently connected together by the transverse bars 17, 18 and 19, forming 65 a rigid bed-frame which can be bodily moved from one place to another without the danger of separation of its parts.

Side-bars 16 have mounted in their upper surfaces, in any desirable manner, a plurality of body-supporting rollers 20, and cross-bar 19 has centrally secured to its rear face and extending horizontally therefrom a U-shaped fulcrum-loop 21, for a purpose hereinafter described.

A wagon-body 22 is mounted on the roller frame and is supported upon the rollers 20, so that it can be easily shifted back and forth to dumping and non-dumping position. Body 22 is retained against transverse 80 movement on the roller frame by the upwardly-projecting stakes 23, which are rigidly secured at their lower ends to the side rails 16 adjacent their ends. These stakes 23 not only serve as guides and retainers for 85 the dump-body, but they are also positioned upon the roller-frame to respectively engage opposite sides of the front and rear bolster standards 15, to serve as a means for retaining the roller-frame against longitudinal 90 movement upon the bolsters.

Wagon-body 22 is preferably constructed with a sheet-metal bottom 24, on the under side of which are secured the transverse braces 25, one being at the rear end of the 95 body and the other at a point approximately midway between the ends thereof. To these braces 25 are secured the ends of a metal dump-strap 26 which is spaced apart from the bottom of the body and whose ends are 100 bent upwardly to engage the braces 25. The forward end of this dump-strap is preferably bent upwardly and backwardly to form a curved loop 27 which is adapted to engage the cross-bar of the fulcrum-loop 21 105 when the wagon-body reaches the dumping position, said fulcrum-loop being positioned in a plane intermediate the height of loop 27 and between the ends of the strap 26. To provide clearance for the movement of strap 110 26 which projects below the bottom of the wagon-body, and to allow the wagon-body

to be supported close to the top side of the roller-frame, the transverse bars 18 and 19 of the roller-frame are recessed, as shown at 28, which provides passageways for the 5 strap 26.

Between the transverse braces 25, there are secured to the metal bottom 24 wooden filling-pieces 29, which are slightly narrower than the width of the wagon-body, so that 10 the extreme side edges of the metal bottom are left exposed to serve as tracks to engage the rollers 20, as clearly shown in Fig. 3 of the drawing. At the same time, the side edges of the fillers 29 serve as side-guides to 15 prevent transverse shifting of the wagon-body in coöperation with both sets of stakes or standards 12 and 23.

Any suitable locking means can be provided for preventing movement of the wagon-body when in its loading or non-dumping position. In the drawing is shown a staple 30 secured to the front end of the roller-frame, which is adapted to receive a removable locking-pin 31 which also engages the 25 bottom of the wagon-body. Stakes 23 are preferably longitudinally adjustable to and from each other upon the roller-frame by means of additional sets of bolt-holes in the frame, as shown at 32, in Fig. 1 of the drawing. This will enable the owner to adjust the locking means of the dumping attachment to fit short or long coupled running gears.

In operation, assuming that the owner has 35 an ordinary non-dumping wagon of the type heretofore described, the body thereof is removed and placed to one side, leaving the bare running gear with its bolsters and standards. Then the improved dumping 40 body and its roller-carrying frame are placed upon the running gear, with the stakes 23 of the roller-frame engaging respectively the opposite sides of the front and rear bolster stakes, thereby effectually locking 45 the dumping attachment in position upon the running gear. When it is desired to dump the body, it is pushed manually to the rear upon the rollers 20, and, at its point of balance, loop 27 engages fulcrum-loop 21 50 and thereby forms a stop for the rearward

movement of the body and at the same time forms a pivot upon which the body will turn to dumping position.

The nature and scope of the invention having been thus indicated and its preferred 55 embodiment having been specifically described, what is claimed as new is:

1. In combination with a wagon running-gear having upstanding side-stakes, a dumping-body attachment comprising a rectangular bed-frame formed with side-bars and cross-bars to enable it to be bodily moved from said running-gear, a wagon-body or box mounted to move longitudinally on said bed-frame, and upwardly-projecting standards secured to said bed-frame and so positioned as to engage the side-stakes of the running-gear to prevent movement of the bed-frame thereon and also to extend upwardly alongside the wagon-body to retain 70 said body upon the bed-frame when the same is removed from the running-gear, and co-operating means on said body and bed-frame for limiting the rearward movement of said body at the dumping position. 75

2. In combination with a wagon running-gear having upstanding side-stakes, a dumping-body attachment comprising a rectangular bed-frame formed with side-bars and cross-bars to enable it to be bodily moved 80 from said running-gear, a wagon-body or box mounted to move longitudinally on said bed-frame, and upwardly-projecting standards secured to said bed-frame and so positioned as to engage the side-stakes of the 85 running-gear to prevent movement of the bed-frame thereon and also to extend upwardly alongside the wagon-body to retain said body upon the bed-frame when the same is removed from the running-gear, 90 said standards also being adjustable longitudinally of said bed-frame to adapt them to running-gears coupled in varying lengths, and co-operating means on said body and bed-frame for limiting the rearward movement of said body at the dumping position. 95

In testimony whereof I hereunto affix my signature.

OSCAR D. ANDERSON.
